ALVINZA F. SIPPERLEY, OF DENVER, COLORADO; SUSIE SIPPERLEY ADMINISTRATRIX
OF ALVINZA F. SIPPERLEY, DECEASED.

PAY-TELEPHONE ELECTRIC RECORDER.

1,222,151.

Specification of Letters Patent. Patented Apr. 10, 1917.

Application filed October 9, 1915. Serial No. 54,992.

To all whom it may concern:

Be it known that I, ALVINZA F. SIPPERLEY, a citizen of the United States, residing at the city and county of Denver and State 5 of Colorado, have invented certain new and useful Improvements in Pay-Telephone Electric Recorders; and I do declare the following to be a full, clear, and exact description of the invention, such as will enable others skilled in the art to which it 10 appertains to make and use the same, reference being had to the accompanying drawings, and to the characters of reference marked thereon, which form a part of this 15 specification.

My invention relates to improvements in means for checking, recording or registering the coins as they are introduced into or delivered to pay telephones. The object or 20 the necessity for an instrument or device of this character is to prevent the possible stealing of money from these phones as frequently happens. It is well known that the losses by this cause, from pay telephones is 25 exceedingly heavy and my object is, by the provision of this checking or registering feature, to make it incumbent upon the collector to turn in with his cash the record made by the machine during any given 30 period. This record may be made by printing certain marks upon a disk of paper or other fabric, the record disk being preferably covered by a sheet of carbon paper and the two being sealed in such a way that the 35 collector cannot gain access to the record for the purpose of altering the same. The disk or sheet upon which the record is made, is carried by a rotary member which has a step-by-step movement automatically 40 imparted after each registering or recording act, in order to bring a new space into the path of the recording or marking element.

As illustrated in the drawing whenever a coin is dropped into the box containing the 45 checking or registering mechanism, it actuates a contact which closes a circuit through the coils of a solenoid and an ordinary electro magnet. The energizing of the solenoid imparts such a movement to the core or 50 plunger as to cause it to strike the carbon paper and make a proper mark upon the recording disk; while the energizing of the ordinary electro magnet actuates a bell crank lever which operates a pawl which in

turn acts upon a ratchet of the disk-carrying member whereby a partial rotary movement is imparted to the latter. As the closing of the circuit is only momentary, the core of the solenoid is returned after each printing act, to its normal position by means 55 of a spring. As there is a separate solenoid for each coin dropped into the instrument, there is a distinct record made for each coin, the record of the nickel, for instance, being indicated on the outermost zone of the recording disk; the record of the dime on an inner zone, the quarters on the zone still nearer the center of the recording disk, and so on, whereby the position of the marks or 60 the zone in which they are located indicates 65 the denomination or value of these marks in figuring the aggregate amount which the telephone in question has earned.

Having briefly outlined my present improvement, I will proceed to describe the 70 same in detail, reference being made to the accompanying drawing, in which is illustrated an embodiment thereof. In this drawing,—

Figure 1 is a front view of a telephone 80 equipped with my improved checking or registering attachment.

Fig. 2 is a side elevation partly in section, the section being taken on the line 2—2, Fig. 1.

Fig. 3 is a front view illustrating the recording or registering mechanism of the instrument, with the front plate and the recording-disk-carrying rotary member removed, the view being taken in the direction 90 of arrow 3, Fig. 2.

Fig. 4 is an inner face view of the front plate and the disk-carrying member, with parts broken away in order to better illustrate the construction.

Fig. 5 is a fragmentary detail section taken on the line 5—5, Fig. 2.

Fig. 6 is a fragmentary sectional detail taken on the line 6—6 of Fig. 4.

The same reference characters indicate 100 the same parts in all the views.

Let the numeral 5 designate a pay telephone instrument, its lower portion having a coin receptacle 6 provided with a lock 7. Above this coin receptacle is the usual 105 casing 8 carrying the transmitter 9 and to the upper portion of which is attached my improved checking or recording device, the

same being designated in its entirety by the numeral 10. This device consists of a casing in which is inclosed a number of solenoids designated 12, 13 and 14 respectively, and an electro magnet 15 which is mounted on a shelf or support 16 above the solenoids. Each solenoid has a core or plunger 17 which is normally held a short distance from a recording disk 18 which is covered by a carbon sheet 19, the two members being connected by seals 20 which may be of any suitable construction. As shown in the drawing this seal consists of a U-shaped piece of fabric which passes around the edges of the recording disk 18 and the carbon sheet 19, and engages the two parts on opposite sides thus making it impossible to separate the carbon from the recording member, for the purpose of altering the record, without leaving evidence that the record has been tampered with. This seal may be of any suitable character and may contain any desired distinguishing marks which will make it practically impossible for the collector to remove the seal without leaving evidence of the act. The extremity of each solenoid plunger is equipped with a recording or printing device 21 which as shown in the drawing is a short, narrow piece of metal adapted when driven against the carbon sheet 19 by the magnetic force developed by energizing the coils of the solenoid, to print marks in different zones on the recording disk, the said zones being indicated by dotted circles designated 22, 23 and 24 respectively, the marks in the outermost zone 22 being those made when the nickel coin is employed to close the circuit; those in the zone 23 being made when the dime is used to close the circuit; and those in the zone 24 being made when the twenty-five cent piece is inserted in the instrument and indirectly performs the circuit closing function.

45 The record disk 18 is mounted on a rotary plate 25 which is journaled on a central projection 26 with which the front plate 27 of the device 10 is equipped, this front plate being hinged to the body of the casing as shown at 28. The outermost zone of the rotary plate 25, is slightly raised as shown at 29 and equipped with ratchet teeth 30 which are acted upon by a pawl 31 which is pivotally mounted on the upper extremity 50 of a bell crank lever 41 fulcrumed on the frame of the magnet 15 as shown at 42, the pawl being held in co-operative relation with the ratchet teeth 30 by means of a spiral spring 34 which is coiled around an arm 40 55 of the bell crank lever, one extremity bearing against the pawl and the other against a weight 32 mounted on the arm 40 of the said lever and serving to actuate the lever and pawl to cause the latter to act upon the ratchet teeth 30 and impart a partial rotary

movement to the plate 25 and the disk 18 carried thereby, immediately after each printing or marking act of the plunger of either of the solenoids 12, 13 or 14 as the case may be. The other arm 43 of the bell 70 crank lever is located in such proximity to the soft iron core 44 of the electro magnet 15, when the said magnet is energized, the magnetism developed will act upon the arm 43 of the bell crank lever and move the lever 75 a sufficient distance, to carry the pawl 31 backward or in the reverse direction from the travel of the plate 25, one ratchet tooth, and as soon as the magnet 15 is deenergized, the weight 32 will act upon the bell crank 80 lever to operate the pawl whereby the latter is caused to actuate the plate 25 as heretofore explained.

The manner of closing the circuit whereby the electro magnetic devices 12, 13, 14 85 and 15 are energized for the purpose heretofore explained will now be described.

The rear portion 45 of the casing of my improved device is provided with a number of coin chutes 46, 47, and 48 in each of which is formed a slot 49 to receive a coin as a nickel, dime, twenty-five cent piece, etc., the upper extremity of each slot being open as shown at 50 for coin receiving purposes. Into these slots respectively project the ends 51 of contact members 52, 53 and 54 respectively, these members being pivotally mounted as shown at 55, but normally held in position to cause their extremities to occupy the slots in the path of the coins, by means of springs 56 connected at one extremity with the top of the casing as shown at 57 and at their opposite extremities with the contact members as shown at 58. Each of these contact members is 105 composed of a good conductor of electricity as some suitable metal. From the contact member 52 leads an electrical conductor 59 to the coils of the solenoid 12, the termination of the said conductor where it connects with the coils of the solenoid being designated by the numeral 60. From the opposite terminal 61 of the coils of the solenoid 12 leads a conductor 62 to one pole 63 of a source of electricity 64 while from the 110 opposite pole 65 leads a conductor 66 to one terminal 67 of the coils of the magnet 15, while from the opposite terminal 68 of said magnet, a conductor 69 leads to a contact bar 70 carrying a number of pairs 71 115 of spaced contacts, one of these pairs being adapted to engage the movable contact as the slot-entering extremity of said contact is moved downwardly by the passage of the coin through the slot 49 whereby the circuit is completed through the solenoid 12 and the magnet 15. As the solenoid is energized, its plunger 17 is caused to strike the carbon sheet 23 and make a mark 72 in the zone 22 120 of the record disk 18, while at the same time 130

the bell crank lever 41 is actuated to move the pawl 31 one ratchet tooth 30 in the rearward direction or the direction opposite the travel of the plate 25 whereby as soon 5 as the solenoid and the magnet 15 are de-energized immediately after the making of the mark in the proper zone on the disk 18, the weight 32 acting on the bell crank lever will move the latter together with the pawl 10 31 a sufficient distance to cause the pawl acting on a ratchet tooth 30, to move the plate 25 and the disk 18 a sufficient distance to bring a new space in the zone 22 of the disk 18 into place to be acted on by 15 the marking or printing extremity 21 of the plunger 17 when the next coin is inserted.

In a similar manner each of the other solenoids 13 and 14 is energized simultaneously with the magnet 15 and marks 73 and 20 74 formed in the zones 23 and 24 respectively of the disk 18. For instance, from the movable contact 53 a conductor 75 leads to one terminal of the coils of the solenoid 13 while a short conductor 76 leads from 25 the other terminal to the conductor 62, the other parts of the completed circuit being the same as heretofore described, when tracing the circuit through the coils of the solenoid 12. Again from the movable contact 30 54 a conductor 77 leads to one terminal of the solenoid 14, while from the opposite terminal of this solenoid a short conductor 78 leads to the conductor 62, the balance of the circuit being the same as heretofore described in connection with the tracing of the 35 circuits through the coils of the solenoids 12 and 13.

From the foregoing description the use and operation of my improved checking or 40 registering device will be readily understood. Of course, the device is capable of use in various ways, so far as the conduct of the collector is concerned. A practicable way of using the device, is to allow the collector, to unlock the coin box 6 and remove the money, and also to unlock the hinged cap 27 by inserting a key in a lock 79. The collector may then remove the record disk and the carbon sheet 19, which are sealed 45 together as heretofore described. He will then deliver this record disk covered by the carbon sheet to the telephone company accompanied by the money removed from the box 6. The carbon sheet will then be re- 50 moved in the office of the company or unsealed, when it is evident the person in charge will be advised as to whether or not the full amount of cash has been turned in. Under such circumstances it is evident that 55 60 the collector will have no opportunity to appropriate a portion of the contents of the cash box to his individual use without the knowledge of his employer. Of course, if practicable or if desired, provision may 65 be made for the removal of the record disk

and its accompanying carbon sheet by a person other than the collector, but in case this is not practicable, or would involve too much expense, it is believed thoroughly practicable to have the record disk removed 70 by the collector, since the same is sealed in such a way that there is no opportunity for him to tamper with it.

In order to prevent the possible return movement of the rotary member 25 due to 75 the pressure of the pawl 31 thereon during the movement of the latter in a direction the reverse of the travel of the plate 25, a friction spring 80 may be employed. This spring bears against the periphery of the 80 plate 25 with sufficient force to maintain the said member in its position of adjustment after each step-by-step movement imparted by the pawl 31.

Having thus described my invention, what 85 I claim is,—

1. In a device of the class described, the combination of a record member mounted to rotate, electro-magnetic means for permanently recording on said member, other electro-magnetic means imparting a step by step movement to the said member after the record has been made thereon, and coin actuated means for simultaneously making and breaking the circuit through the two electro- 95 magnetic means.

2. In a device of the class described, the combination of a record member mounted to rotate, electro-magnetic devices for permanently recording on said member, a second electro-magnetic device for imparting a step by step movement to said member after the record has been made thereon, said second device being arranged in series with the first mentioned device, and coin actuated 100 means for simultaneously making and breaking the circuit through both sets of devices.

3. In a device of the class described, the combination of a record member mounted to rotate, a number of independently operable 110 electro-magnetic devices arranged to print on said member as the said devices are energized, a second electro-magnetic device arranged to impart a step-by-step movement to the record member after each printing act, 115 and means for simultaneously making and breaking the circuit through any one of the first named electro-magnetic devices and the second named electro-magnetic device, a part of said circuit make-and-break means projecting into the path of a coin during its travel through the instrument.

4. A device of the class described including a casing having a number of coin chutes, movable contacts arranged to project into 125 the passages through said chutes, solenoids connected in operative relation with the said contacts, the latter being actuated by coins inserted in the said chutes and arranged to close circuits through the respective sole- 130

- noids, a member rotatably mounted and arranged to receive marks or prints as the plungers of the solenoids are actuated during the closing of their respective circuits to engage said member, an electro-magnet located in the circuit of each solenoid, and means operable by said magnet for imparting a step-by-step movement to the record member for the purpose of bringing a new printing surface into line with the marking or printing device of any solenoid after the latter has performed the printing or marking act.
5. A device of the class described including a casing having a number of coin chutes, a record disk divided into zones and mounted to rotate, electro-magnetic devices each arranged to print in a different zone on said disk, a second electro-magnetic device located in the circuit of each of the printing electro-magnetic devices, for imparting a step-by-step movement to the record disk after each printing act, and means for making and breaking the circuit through each of the electro-magnetic printing devices and the electro-magnetic device for imparting rotary movement to the record disk, a part of the circuit make-and-break means project-
- 10
- 15
- 20
- 25

ing into each coin chute and into the path of a coin passing therethrough.

6. A device of the class described including a number of coin chutes, a record disk mounted to rotate, a number of electro-magnetic devices arranged to print in different zones on said disk, the latter having a printing surface covered by carbon paper arranged to be acted on by the printing device, an electro-magnetic device for imparting a step-by-step movement to the disk, the electro-magnetic device for imparting the step-by-step movement to the record disk being located in the same circuit with each of the electro-magnetic printing devices, and means for making and breaking the circuits through each of the electro-magnetic printing devices and the electro-magnetic disk actuating device, a part of the make-and-break device projecting into a coin chute and into the path of a coin passing therethrough substantially as described.
